UNITED STATES PATENT OFFICE.

NATHAN P. DAZEY, OF ST. LOUIS, MISSOURI.

DISPENSER FOR STRAWS AND OTHER ARTICLES.

1,010,121.

Specification of Letters Patent. Patented Nov. 28, 1911.

Application filed June 9, 1910. Serial No. 566,072.

To all whom it may concern:

Be it known that I, NATHAN P. DAZEY, a citizen of the United States of America, residing at the city of St. Louis, in the State 5 of Missouri, have invented certain new and useful Improvements in Dispensers for Straws and other Articles, of which the following is a full, clear, and exact description, reference being had to the accompanying 10 drawings, forming part of this specification.

My invention relates to a holding and dispensing device more particularly intended for use in holding and dispensing straws 15 commonly used at soda water fountains and other places where drinks are served and are intended to be drawn into the mouth by the use of straws.

The object of my invention is to provide 20 a device of this kind into which straws may be placed to be kept in a sanitary condition and to be dispensed singly when they are to be used.

Figure I is a front elevation of my holder 25 and dispenser, part of one end of the device being shown in vertical longitudinal section. Fig. II is in part an enlarged end elevation and in part a vertical cross section taken through one of the end plates or end 30 frames. Fig. III is an enlarged vertical cross section through the barrel of my device, with the operating mechanism present 35 at the opposite end of the device from that shown in Fig. II in elevation, the joggling or agitator disk at this end being removed. Fig. IV is an enlarged fragmentary perspective view of portions of my device adjacent the discharge opening and showing the 40 closure for said opening and operative connections for the same. Fig. V is a fragmentary section illustrating the manner in which the straws are discharged from the receptacle.

Referring more particularly to the drawings, a receptacle 1 for holding the articles to be dispensed is in the present exemplification provided in the form of a cylindrical barrel provided at its top with an inlet opening 2 through which in the present instance, 50 straws may be introduced into the barrel. Said barrel is preferably provided with two downwardly discharging outlet openings 3 and 4 disposed above the bottom of the receptacle.

55 5 and 6 are the end plates or frames between which the barrel 1 is held and sup-

ported, said end plates being respectively provided at their inner faces with segmental flanges 5' and 6' into which the fastening means for holding the barrel to the end 60 plates, such as screws, are inserted and pass through the barrel where it is fitted around such flanges.

7 designates a rock shaft extending longitudinally through the barrel 1 and the 65 ends of which are rotatably mounted in the end plates 5 and 6. This rock shaft serves as a support for the means by which the straws are discharged through an exit-way 70 of the barrel 1, and I will first in the following description set forth the parts as they are utilized to discharge straws through the discharge opening 3. This ejector device comprises hangers or arms 8 and 8' located respectively near the end plate 6 and 75 the end plate 5 and held to the rock shaft by suitable means, such as set screws 10, and the ejector device also comprises a bar 11 supported by the hangers and which preferably includes a fin 12 that is adapted to 80 travel in an arc of a circle in close proximity to the bottom of the barrel 1 when the ejector device is swung to and fro. Fin 12, extending centrally downward from the upper flange of the ejector 11, constitutes a recess 85 on each side of the ejector 11 of sufficient depth to receive and trap a straw, upon movement of the ejector.

9 and 9' are lever arms that receive connections by which the rock shaft 7 is rotated and the ejector device is swung to and 90 fro. These lever arms may be made either integral with the hangers of the ejector device or separate therefrom and attached to either the hangers or the rock shaft. The 95 lever arm 9, which is at one end of my straw holder at or adjacent to the hanger 8 has pivotally connected to it a link 13.

14 is a stub shaft rotatably mounted in the end plate 6 and which has fixed to it at its 100 inner end a lever arm 15, that is pivotally connected at 16 to the link 13.

17 is an operating lever by which rotation is imparted to the stub shaft 14 and which is fixed to said stub shaft at its outer 105 end and is provided with a finger button 18. In the actuation of the ejector device to move the ejector bar 11 toward the exit-way 3, the operating lever 17 is depressed and imparts rotation to the stub 110 shaft 14 whereby upward movement is imparted to the lever arm 15 located interiorly

of the straw holder and the link 13 is actuated to impart movement to the lever arm 9, with the result of moving the hanger 8 in an arc of a circle. Inasmuch as the 5 hanger 8 is fixed to the rock shaft 7, said rock shaft is rotated and the hanger 8' at the opposite end of the holder is caused to partake of the same movement as the hanger 8 and the ejector bar 11 is moved in a direction corresponding to that of the hangers; that is to say, in a direction toward the discharge opening 3. Upon the release of pressure upon the operating lever 17, the 10 ejector device is returned to its normal position through the medium of retracting members, (see Fig. II), comprising an arm 19, extending rearwardly from the hanger 8 relative to the operating lever 17, a retracting spring 20 connected to said arm, 15 and a spring receiving member 21 that is supported by an adjustment screw 22 mounted in the flange 6' of the end plate 6, and which is adapted to be adjusted to move the member 21 thereon to vary the 20 tension in the retracting spring 20, in order that it will act properly upon the ejector members to return them to their normal positions after the ejector bar 11 has been moved toward the exit-way 3.

25 30 23 designates a gate that controls the exit-way 3. This gate extends longitudinally of said exit-way and its free edge, which faces the ejector bar 11, is provided with a pocket 24. The gate is mounted at 35 its forward edge upon a rock shaft 25 journaled in the end plates 5 and 6 and has fixed to it, adjacent to the end plate 6, a crank arm 26, (see Figs. III to V, inclusive.) The crank arm 26 is, as will be ob- 40 served, at the end of the straw holder opposite that at which the previously described ejector device operating members are located.

27 is a gate operating rod that is pivoted 45 at its lower end to the crank arm 26 and is operable in an eye or guide 28 supported by the flange of the end plate 5. This rod is provided, (as most clearly seen in Fig. IV,) with an abutment 29, between which 50 and the guide 28 is a spring 30 that serves to impart a downward movement to the gate operating rod after it has been actuated in the manner to be presently explained.

55 31 is a lift finger carried by the hanger 8' of the ejector device and the free end of which is adapted to travel alongside of the gate operating rod 27 when the ejector device is swung forwardly to carry the 60 ejector bar 11 toward the discharge outlet 3. As said ejector bar approaches said discharge opening, the lift finger 31 rises into engagement with the abutment 29 and by upward pressure thereagainst acts to elevate the pull rod 27, with the result of 65 imparting rotation to the rock shaft 25 whereby the gate 23 is elevated from the position seen in Figs. III and IV to the position seen in Fig. V, in order that the ejector bar 11 may discharge a straw through the 70 discharge opening 3. The actuation of the gate in the manner stated is accomplished upon the operation of the ejector device through the medium of the operating lever 17, as hereinbefore described, and when 75 said lever is released and the ejector device returns to its normal position, the spring 30 acts to return the gate 23 to a closed position. In this connection, it should be stated that the actuation of the 80 ejector bar 11 and the gate 23 are so timed relative to each other as to provide for the gate being opened just previous to the ejector bar being brought into close proximity with the rear free edge of the gate 85 so that only a single straw located in front of the fin 12 of the ejector bar will be delivered to the discharge opening, as indicated in dotted lines Fig. V, while any straws above the ejector bar will either 90 rest thereon, or be carried over into the pocket 24 of the gate to remain in such positions pending the closing of the gate when the ejector bar returns to its normal position. As the ejector 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 down the incline of the exit-way. As the 5 ejector 11 recedes, the gate 23, under action of its operating rod, and the spring 30, acts in closing, quickly enough to prevent the escape of additional straws. As the ejector 10 returns to its normal central position, the mass of straws ride over the same. This is an important feature, inasmuch as regardless of which side of the machine is operated to the greatest extent, the ejector, in moving to and fro, distributes the straws on each side of it by passing under them.

Mention has hereinbefore been made of the fact that my straw holder and dispenser 15 is provided with two discharge openings or outlets and in the preceding description I have in the main referred to the straw dispensing parts only in so far as they are concerned in the discharge of straws through 20 the discharge outlet 3. The object in having a second discharge opening 4 is to provide for the straws being discharged at the side of the straw holder opposite that containing the discharge outlet 3 or what, in 25 view of the previous description, might be properly termed the back of the straw holder, and the provision of means that permits of the dispensing device being operated at either of its ends. Inasmuch as the

30 discharge outlet 4 is located opposite to the discharge outlet 3, it will be noted that to discharge straws through the discharge outlet 4 it is only necessary to operate the ejector device in a direction the reverse of 35 the direction in which it is moved to discharge straws through the discharge outlet 3, and that consequently the ejector device operating members, similar to those previously described, but disposed reversely

40 relative to the first described, will provide for the desired dispensing of straws through the discharge outlet 4. The lever arm 9' at the end of the straw holder at which the hanger 8' is located therefore has connected 45 to it a link 13' to which is pivoted at 16' a lever arm 15, fixed to a stub shaft 14', loosely mounted in the end plate 5. This stub shaft is operated by an operating lever 17' having a finger button 18'. It will be

50 noted that the parts just set forth being located at the opposite end of the straw holder from that at which the operating lever and its companion parts are located, when the operating lever 17' is depressed, the ejector 55 device, including the ejector bar 11, will be moved toward the outlet opening 4. The gate 23' that controls the discharge outlet 4 is operated similarly to the gate 23 that controls the discharge outlet 3; that is

60 to say, it is supported by a rock shaft 25' provided with a crank arm 26' to which is connected a pull rod 27', the pull rod being provided with an abutment 29' and surrounded by a spring 30'.

65 31' is a lift finger carried by the hanger

8 of the ejector device, and through the medium of which the pull rod 27' is actuated, due to the engagement of said finger with the abutment 29'. The pull rod 27' serves to actuate the gate 23' in the same 70 manner as the gate 23 is operated upon the lift finger 31' being brought into engagement with the abutment 29' when the ejector bar 11 is moved to the gate 23', and with the result of a straw being discharged 75 through the discharge outlet 4.

32 designates agitator disks attached to the hangers 8 and 8', these disks being located at the ends of the chamber in which the straws are present when the holder acts 80 against the ends of the straws and keep them stirred up in such manner so as to provide for their assuming parallel positions in the chamber at its bottom to be in proper positions to be engaged by the fin 12 of the 85 agitator bar 11.

While I have described my holder and dispenser as intended more particularly for use in holding and dispensing straws, it is 90 obvious that it may be utilized for dispensing other articles, and I therefore do not limit myself to its use for dispensing any particular article.

I claim:—

1. In a device of the character described, 95 the combination with a receptacle provided with a discharge outlet, of an inwardly opening gate normally barring the passageway through said outlet, an ejector movable to and from said outlet, said ejector 100 being provided with a recess for containing but a single article, and gate opening means adapted to hold the gate in an open position with edges abutting said ejector above said recess whereby said recess is placed in open 105 communication with the exterior of said receptacle through said discharge outlet.

2. In a device of the character described, 110 the combination with a receptacle provided with a discharge outlet, of a gate normally barring the passageway through said outlet, an ejector movable to and from said outlet, said ejector being provided with a recess for holding only a single article to be dispensed, and gate opening means operable 115 only when said ejector is brought into proximity to said opening, said gate being adapted in open position to form a bridge between the wall of said receptacle and said ejector above said recess whereby said recess 120 is placed in open communication outwardly through said discharge outlet.

3. In a straw holder, the combination with a cylindrical receptacle with its axis horizontal, said receptacle being provided 125 with a discharge outlet above the bottom thereof and extending longitudinally of the cylindrical wall thereof, a gate movable about an axis adjacent the upper edge of said outlet and normally barring said out- 130

let, an oscillating ejector having its outer end swinging along the cylindrical wall to and from said outlet and having a straw holding recess adjacent said outer end, and means operably related to said ejector for swinging said gate inwardly when said ejector is brought into proximity to said outlet, said means being adapted to raise said gate into a position to bridge said discharge outlet and to provide an abutment for said ejector, the swinging edge of said gate being in this position in contact with said ejector above the recess in its outer end to permit the ejection of the straw in said recess.

4. In a straw dispenser, the combination with a cylindrical housing disposed with its axis horizontal, said housing being provided with a longitudinal discharge outlet, an ejector normally distant from said outlet, said ejector being provided with a straw holding recess parallel to said outlet, means for moving said ejector into and out of a position in which said recess is in proximity to the lower edge of said outlet, a gate hinged on an axis adjacent the upper edge of said outlet, and means for swinging said gate into open position when the ejector is in proximity to said discharge outlet, said gate forming a bridge between the upper edge of said outlet and said ejector at a point immediately above said recess.

5. In a device of the character described, the combination with a receptacle having a curved inner wall and a discharge opening above the bottom of said receptacle, a closure for said opening movably related to said opening, an ejector movable toward and away from said opening, means for resiliently holding said closure in closed position, and means carried by said ejector into and out of operative engagement with said holding means.

6. In a device of the character described, the combination of a cylindrical receptacle for articles to be dispensed provided with spaced longitudinal discharge openings, an ejector mounted to swing to and fro between said openings, a closure for each of said openings, means for resiliently holding said closures in closed position, and means carried by said ejector for operatively engaging said holding means.

7. In a device of the character described, the combination of a receptacle provided with spaced longitudinal discharge openings, with an ejector mounted to swing to and fro between said openings, a closure for each of said openings, means for resiliently holding said closures in closed position, and means carried by said ejector for operatively engaging said holding means.

8. In a device of the character described, the combination of a cylindrical receptacle for articles to be dispensed, disposed with

its axis horizontal and having longitudinal discharge openings on opposite sides of the vertical plane through said axis, an ejector mounted to swing about said axis between said discharge openings, an operating lever, and means operatively connecting said lever to said ejector, said means being adapted to produce a greater angular movement of the ejector than is undergone by said operating lever.

9. In a holder and dispenser, a barrel having an exit-way, a gate controlling said exit-way, an ejector device oscillatorily mounted in said barrel and comprising an ejector bar having a fin at its lower edge, and means for opening said gate upon the approach of said ejector bar to the gate; and said gate being provided at its free edge with a pocket adapted to coincide with said ejector bar when the ejector bar is brought into proximity with the gate.

10. In a device of the character described, the combination of a receptacle for straws to be dispensed, said receptacle being provided with a longitudinal opening, a closure for said opening, and an ejector for the straws, and means operatively connecting said closure to the ejector, said ejector being provided with a recessed portion coöperating with the closure in open position to close said opening against all but one straw.

11. In a device of the character described, the combination with a receptacle provided with a discharge opening above the bottom of said receptacle, an inwardly-opening closure for said opening, said closure being provided with a rounded inwardly turned nose, an ejector movable toward and away from said closure, said ejector being provided with a recessed portion coöperating with the closure in open position to close said opening, and means operatively connecting the closure to said ejector.

12. In a device of the character described, the combination with a receptacle having a suitable discharge opening and end plates, of an operating shaft extending longitudinally through said receptacle, movable joggling plates mounted within said receptacle near each end of said shaft, an ejector bar located in the bottom of said receptacle, arms supporting said bar at its ends and located between said plates and the end plates of the receptacle, and means for operating said shaft.

13. In a device of the character described, the combination with a receptacle having a suitable discharge opening and end plates, of an operating shaft extending longitudinally through said receptacle, movable joggling plates mounted within said receptacle near each end of said shaft, an ejector bar passing through said joggling plates and located in the bottom of said receptacle, arms supporting said bar at its ends and

located between said plates and the end plates of the receptacle, and means for operating said shaft.

14. A holder and dispenser comprising a barrel having end plates and a longitudinal exit way, an ejector device consisting of a longitudinal rock-shaft, hangers fixed to the rock-shaft, and a bar carried by the hangers, an arm extending from the ejector device, 5 an adjustment screw, a receiving member carried by the adjustment screw, a spring connecting the arm with the receiving member, and means for operating the rock-shaft.

15. A holder and dispenser comprising a barrel having end plates and a longitudinal 15 exit way, an ejector device having a lift finger, a gate controlling the exit way consisting of a longitudinal rock-shaft, a crank-arm fixed to the rock-shaft, a gate operating spring rod pivoted at its lower end to the 20 crank-arm, and having an abutment engaged by the lift finger.

NATHAN P. DAZEY.
